Millstone Exhaust.

Patented May 6, 1813.

Cross Section.

John Stowley 1922X
Geller Patent

The Schedule referred to in these Letters Patent and making part
the same containing a description in the words of the said John
Geller himself of his flour mill:

This machine is composed
of an upright shaft or axis with a cog head geared into the
wheel work of the mill, second two arms equal in length
to the diameter of the worm. these arms are confined together and
adjusted to receive the upright shaft on which they move up & down
easily. Third to the under side of these arms is attached the worm
commencing near the centre or upright shaft, and describing
a line spiral line to the circumference. The angle which this
spiral line forms with the radii may be greater or less as it is
required to deliver the flour quicker or slower. this too may be
regulated by the motion of the machine. Fourth there is attached
to the worm a thin hoop descending, a small distance below
its plane forming a lip or ledge. The machine being thus
constructed is put into a rotary motion by means of the cog head
and the flour being convoluted within its vortex or circumference
the plane of the worm floats on the surface of the flour rising
or sinking, on its axis at the same time the lip or ledge separating
the flour by its spiral motion conveys it gradually to
the centre where it is discharged on the bolt or by reversing the
motion of the machine the flour may be discharged at its circum-
ference.
